(57) **CLAIM**

The ornamental design for a pacifier, as shown and described.

DESCRIPTION

FIG. 1 is a front elevational view of the pacifier;
FIG. 2 is a rear elevational view of the pacifier;
FIG. 3 is a top plan view of the pacifier;
FIG. 4 is a bottom plan view of the pacifier;
FIG. 5 is a side elevational view of the pacifier taken from the right side; and,
FIG. 6 is a side elevational view of the pacifier taken from the left side.

The broken line showing of the nipple is for illustrative purposes only and forms no part of the claimed design.
